CLAIM

The ornamental design for a flower bulb container as shown and described.

DESCRIPTION

FIG. 1 is a top, front perspective view of a flower bulb container showing my new design;

FIG. 2 is a bottom, back perspective view thereof;

FIG. 3 is a front elevational view thereof, the back, right side, and left side elevational views all being mirror images thereof;

FIG. 4 is a top plan view thereof;

FIG. 5 is a bottom plan view thereof; and,

FIG. 6 is a cross-sectional view as seen along lines 6-6 in FIG. 4.

The portion of the flower bulb container shown in broken line forms no part of the claimed design. The alternating dash dot lines define the bounds of the claimed design and form no part thereof.
